[57] CLAIM

The ornamental design for a cluster type telephone booth, as shown and described.

DESCRIPTION

FIG. 1 is a front perspective view of a cluster type telephone booth showing our new design.

FIG. 2 is a top plan view thereof.

FIG. 3 is a front elevational view thereof.

FIG. 4 is an elevational view of FIG. 2 showing the display unit.

FIG. 5 is a view taken along line 5—5 of FIG. 2 showing one of the three individual telephone booths in elevation, the other two booths of the cluster being identical thereto.

FIG. 6 is a front perspective view of a modified form of our new design identical to the design of FIGS. 1—5, except that a four-booth cluster is shown.

FIG. 7 is a top plan view of the design shown in FIG. 6.

FIG. 8 is a front elevational view of the design shown in FIGS. 6 and 7.

Fig. 5.

Fig. 4.
